Atty's

UNITED STATES PATENT OFFICE.

GEORGE E. JANES, OF LOS ANGELES, CALIFORNIA.

BRUSH GUIDE FOR COMPASSES.

Application filed May 7, 1923. Serial No. 637,201.

To all whom it may concern:

Be it known that I, GEORGE E. JANES, a citizen of the United States, residing at Los Angeles, in the county of Los Angeles 5 and State of California, have invented new and useful Improvements in Brush Guides for Compasses, of which the following is a specification.

My present invention being a brush 10 guide and regulator, it is a primary object of this invention to provide means, preferably comprising the usual elements of a compass, whereby substantially uniform circles may be accurately drawn by means 15 of a brush, and whereby the drawing of uniform straight lines by means of a brush may also be facilitated.

It is an object of this invention to provide simple means, suitable for use by sign 20 writers, industrial artists, and others, for limiting the amount of pressure that can be applied to an artist's brush, and providing a plurality of points spaced from the tip of a brush, either of which points may be used 25 as a pivot or as a gliding guide movable relatively to a straight edge, or the like; and in a preferred embodiment of my invention, adapting a brush to be used as one 30 leg of an adjustable pair of compasses, I employ an additional leg or finger adapted to be secured by an adjusting screw of a pair of compasses, this mentioned additional leg or finger being preferably slotted and bent, as hereinafter described.

It being understood that the character of 35 a line drawn by a brush, assuming a uniform supply of paint or ink thereto and a uniform angle of inclination, may depend not only upon the uniformity of motion but upon the uniformity of the applied pressure 40 (determining the spread of the brush), it is an object of this invention to provide adjustable pressure regulating means adapted to serve also as guides and preferably comprising a plurality of points or tips spaced 45 from the tip of a brush, said means being advantageously associated with compass parts and a novel attachment adapted to be adjustably secured thereto.

Other objects of my invention will appear 50 from the following description of a preferred embodiment thereof, and from the appended claims, taken in connection with the accompanying drawings, in which—

Fig. 1 is a perspective view illustrating

the mode of using my invention in the drawing of a circle.

Fig. 2 is a perspective view showing the mode of using my device in the drawing of a straight line, using a ruler, or the like, 60 as a guide.

Referring to the details of that embodiment of my invention which I have chosen for illustration, 1 is an adjustable leg of a compass, this leg being pivoted at 2 to a 65 clip 3 which may have been intended to receive a pencil, but which, being resilient, is suitable to receive a brush 4, or the like, adjustment being effected by means of the link 5, provided with a slot 6, and with a 70 screw 7, shown as provided with a milled head 8.

Coming now to the strictly novel features 75 of my invention, 9 is a finger, which may be of any suitable configuration, but which is shown as bent at 10, and rebent at 11, to provide an offset avoiding contact with the brush 4, and enabling the tip 12 of the finger 9 and the tip 13 of the leg 1 to co-operate in regulating the application of 80 pressure upon the tip 14 of the said brush while the same is guided by the tip 13 in the drawing of a circle, as shown in Fig. 1, or in the drawing of a straight line, as shown 85 in Fig. 2.

Although I have shown in Fig. 2 the use 90 of a straight edge 15, as a means for guiding the tip 13 of the compass leg 1, it will be understood that any equivalent means, having any desired curvature, such as a scroll commonly used by draftsmen, may be substituted therefor; and it will be understood also that, by means of the slot 16, through which the screw 7 is adapted to extend, the parts referred to may be spaced 95 suitably to the drawing of circles of any desired diameter, or suitably to the drawing of parallel lines at any desired relative distances from a guiding edge. It is advantageous, although not indispensable, that the points 12 and 13 shall be disposed on opposite sides of the tip of the brush, as shown in the illustrations; and it is advantageous 100 that the three points referred to shall fall approximately in a straight line, due allowance being made for the inclination and the bending of the brush.

Although I have described one complete 110 embodiment of my invention, it will be understood that various features thereof may

be independently used, and that various modifications might be made without departure from the spirit and scope of my invention as the same is indicated above and in 5 the following claims.

What I claim is:

1. The combination with a compass leg and a socket adjustably connected to the leg, 10 of a finger adjustably connected to the leg and adapted to bear at the opposite side of a brush in the brush holder from the leg.
2. A brush guide comprising a compass leg, a clamp adapted to hold a brush adjustably connected to the upper end of the leg, 15 and a finger adjustably connected to the upper end of the leg and bent laterally so that a brush may be mounted in the brush holder and bear between the points of the leg and finger.
- 20 3. A brush guide comprising a compass leg, a clamp adapted to hold a brush pivotally connected to the upper end of the

brush leg, a slotted link connecting the clamp to an intermediate portion of the compass leg, an adjusting screw in the slot and compass leg, and a finger having a slotted upper end to fit under the head of the clamping screw, said finger being bent laterally so that a brush in the brush clamp will be between the tips of the compass leg and finger. 25 30

4. A brush guide comprising the combination with a compass leg, a clamp pivoted to the upper end of the compass leg and forming a brush holder, a link connected to the clamp and having a slot, an adjusting screw passing through the slot and connecting the clamp to the compass leg, and a finger adapted to be held adjustably in place by the clamping screw and adapted to bear at the 35 opposite side of a brush in the brush holder 40 from the leg.

In testimony whereof I have signed my name to this specification.

GEORGE E. JANES.
